UNITED STATES PATENT OFFICE.

FRANK J. ROWSE, OF PAWTUCKET, RHODE ISLAND.

LOCK.

1,201,632.

Specification of Letters Patent.

Patented Oct. 17, 1916.

Application filed April 15, 1914. Serial No. 832,116.

To all whom it may concern:

Be it known that I, FRANK J. ROWSE, a citizen of the United States, residing at No. 453 Cottage street, Pawtucket, in the county 5 of Providence and State of Rhode Island, have invented a new and useful Improvement in Locks, of which the following is a specification.

My invention is an automatic closure for 10 locks and particularly for a coin-controlled locking mechanism such, for example, as that disclosed in Letters Patent of the United States, No. 1,043,033, issued to me, the said Frank J. Rowse, on October 29, 15 1912, but its use is not limited to that particular device for it can be used advantageously in connection with other devices whether coin-controlled or not.

The purposes of my invention are to provide 20 an automatically locking closure for an auxiliary opening into the lock, such as the sight or reading opening through which may be read the counter that records the number of times the device has been coin-operated; to provide that access to the interior of the lock shall not be had through the auxiliary opening except through the instrumentality of a supplementary bolt controlling device; to provide a closure for the 25 auxiliary opening to conceal from the public the record of the coins accumulated, to protect the delicate mechanism of the counter which records the accumulation of coin and particularly to shield from breakage the 30 35 glass face of the counter.

In the accompanying drawings like reference numerals indicate like parts.

Figure 1 is a perspective view of the upper portion of a lock-box or case of a coin-controlled locking mechanism wherein my improved supplementary controlling device and coöperating parts are located. Fig. 2 is a top plan view of the same device and parts shown in position within the lock-box 40 or case, as seen at a section on the line $y-y$, of Fig. 1. Fig. 3 is a front elevation of the supplementary-controlling device and its associated parts. Fig. 4 is a rear elevation of the front plate or casting of the box or case, 45 with a portion of an operating lever of the coin-controlled mechanism shown in elevation. Fig. 5 is a side elevation of the cylinder of the lock and certain associated parts. Fig. 6 is a side elevation of the key for said

lock. Fig. 7 is a top plan view of the detachable plate 20 which supports the supplemental device and its conjoined parts, in position within the case. Fig. 8 is a front elevation of the detachable plate showing the rocker-arm 32, which, when actuated by the coin-mechanism, operates the counter and it also shows the means for preventing the withdrawal of the key from its position in the lock when turned from its entering position, as hereinafter described. 55 60 65

In the drawings, like reference characters indicate like parts.

The upper portion of the case or lock-box is shown in Fig. 1, comprising the front 1, the top 2 and the side 3. The opposite side 4 is seen in Figs. 2 and 4. Through the front 1 is an aperture or slot 5 for the insertion of the coin, by which (in connection with associated parts) the principal bolt controlling mechanism within the case is 70 75 operated. Said principal bolt controlling mechanism is not shown in the drawings, except a lever thereof marked 18 and hereinafter described. There is a rectangular aperture 6 through the front 1, near the upper left-hand corner, as seen in Fig. 1, which may be called the "reading slot." Near one upper corner is a circular aperture 7, which is the front bearing for the cylinder C of the supplementary bolt controlling device. 80 85 A rectangular aperture 9 through the side 3 receives a fixed supporting lug, and through a rectangular aperture 10 of the side 4 of the case is inserted the separable lug of a supporting plate 20, on which is mounted 90 the counter and the rear bearing 34 for the cylinder C.

Referring to Fig. 4, two ridges, 11 and 12, are cast integrally with the case-front. These constitute ways or guides for a slide-plate or closure 13. The slide-plate 13 has a lip 14, extending from the adjacent edge at a right angle. A small hole 15 is made through the slide-plate near the outer end thereof. A projection 16 cast with the case-front 1, serves as an abutment or stop to limit the outward movement of the slide-plate 13 and there is also an overhanging lip 16^a to hold the slide plate to the ways. 95 100 105

The case-front 1 has a round beveled-edged depression 17, across the bottom of which the coin-slot 5 extends diametrically. The two opposite long edges of the slot 5

are beveled to facilitate the insertion of the coin through said slot to actuate the coin-controlled mechanism.

In Fig. 4 is shown only so much of the coin-controlled mechanism as communicates movement to the counting-device hereinafter described, which constitutes a portion of my present invention. The part so illustrated is the extreme, upper, free end of a lever 18, 10 pivotally mounted on a proper support (not shown), from which lever a cylindrical stud 19 projects.

The supplementary bolt controlling device, and my automatic closure, with operative connections, which constitute my present invention, are secured in position within the box or case, upon the supporting plate 20. The plate 20 is substantially rectangular in outline and has, at and near one corner, a lip 21, preferably integral with the plate, extending therefrom at a right angle, the end 22 of which lip is widened, as shown in Figs. 2 and 7.

A block 23, formed with a lug 24, is secured by rivets 25 or otherwise, to the supporting plate 20. This lug is inserted through the slot 9 in the side 3 of the case. Another lug 26 projects from a rectangular block 27, with which it is integral and is attached to the plate 20 by a screw 28. The block 27, with its lug 26 is thus detachable from the supporting plate 20 at will, whenever the screw 28 is removed.

A shouldered stud 29 is riveted to the supporting plate 20, and on the reduced bearing portion 31 of said stud is mounted the rocker arm 32, which has a notch or yoke slot 33 to engage the counter whereby movement of the said rocker arm causes operation of the counter. This rocker arm is oscillated from the position shown in Fig. 8 in solid lines to the position shown therein by dotted lines (and vice versa) by means of the stud 19 of the lever 18 (Fig. 4), which lever is operated 40 by said coin-controlled mechanism (not shown), the direction of the movement of the stud being indicated in Fig. 8 by the arrows *f* and *g*. The two dotted circles marked 19^a and 19^b, and the arrow *f* show successive 45 positions and the direction of movement of said stud when this mechanism is moved without a coin therein, while the arrow *g* and the two dotted circles marked 19^c, 19^d, show the direction of movement and successive operative positions of said stud when a coin 50 has been inserted in the said coin controlled mechanism.

The supporting plate 20 is also provided with a circular locking disk 34, supported on 60 a stud or body 35 of substantially smaller diameter (Fig. 8), the stud being riveted, as shown, or otherwise fastened in position on said plate, and the circular disk having a radial slot 36 in its edge. This locking disk 65 constitutes a trunnion or rear bearing for the

cylinder of the supplementary bolt controlling device.

A counter, comprising a series of registering dials 38 or other enumerating members, has a case 39, which is provided with the 70 bracket plates 40, 40, screws 41, 41, secure the counter by these bracket plates to the supporting plate 20, as illustrated in Figs. 2 and 3. The screws 41, 41, each pass through a cylindrical spacing block 43 (Fig. 2). 75

On the shaft 44 of the counter is mounted an arm 45, having a split hub 46 whereby said arm is secured to the shaft 44 by a binding screw 47. This arm 45 extends from the shaft 44 and at its free end enters the slot 33 80 of the rocker arm 32, (Fig. 3) and is oscillated, as indicated in Fig. 8.

The supplementary bolt controlling device comprises a cylinder C mounted by one end in the bearing 7 in the front *i* of the lock case, 85 and by the other end on the trunnion or locking disk 34 on the supporting plate 20. Preferably the cylinder is made in two parts, a solid body or plug 8^a, and a sleeve or barrel 48 in which the plug 8^a is secured, as by a pin 49, the projecting portion of the plug 8^a serving as a gudgeon or bearing for the cylinder C, to bear and work in the aforesaid bearing 7 of the front plate 1. In the plug 8^a is formed a keyway with wards to conform to 90 the shape of the key, shown in Fig. 6. The cylinder C is capable of rotation through about 90 degrees, by the key 51, inserted through the key hole 52 in the face of the cylinder, into the keyway aforesaid. Projecting from the cylinder is a cam 67, integral therewith, and whose edge 68 is eccentric to the axis of the cylinder. A bolt actuating arm 69 is also integral with the sleeve 48 and extends therefrom parallel to the cam 100 67 (Figs. 2 and 5). The bolt actuating arm 69 contacts with a lug 70 of the bolt 71, as shown in Fig. 3, and works the bolt 71 in the guide slot 72 in the side 3 of the case 1 (Fig. 1). 105

Having described the several parts of my invention I will now explain its operation, as applied to the lock of a pay closet or apartment, such as is disclosed in my said Letters Patent No. 1,043,033. 110

The lock to which my invention applies comprises two bolt controlling devices, one principal and the other supplementary. The principal bolt controlling device is coin operated and is operated by a patron who 115 desires to unlock the door and so gain access to the closet or apartment. He inserts a coin of the proper size and denomination through the coin slot 5. This coin, while it is temporarily in position in the locking mechanism, is itself a member or active element in the combination, so that when the patron manually turns the handle (not shown) of the door, he can operate the locking bolt 71 to remove it from its en- 120 125 130

gagement with the casing of the door or with a catch secured thereto, each coin operated movement of the bolt being recorded by the counter. As explained the dotted 5 circles 19^c and 19^d show successive positions of the stud 19 of the lever 18 when the principal bolt controlling mechanism is actuated through an inserted coin. The movement of the stud 19 of the lever 18 from the position 10 shown at 19 in Fig. 8 to the position shown at 19^c in said figure, causes the said stud to encounter the rocker arm 32 and further movement from 19^c to 19^d causes an oscillation of the rocker arm 32, upon its pivot 31 from its 15 position shown in solid lines to its position shown in dotted lines. As its slot 33 engages the arm 45 of the counter, each such oscillation causes one depression of the counter arm 45 and consequently advances 20 the counter register one unit. The supplementary bolt controlling device is available to unlock the door of said closet or apartment without the use of a coin for that purpose and without recording the bolt movement 25 on the counter; and it also operates the slide which normally covers, protects and conceals from sight the register of the counter, or permits said register to be exposed at the will of the proprietor who wishes to 30 ascertain how many coins have been inserted in the mechanism to work the same. The supplementary bolt controlling device is operated by inserting the key 51 in the keyhole 52 and turning it in the direction 35 of the arrow *h*, which action turns the cylinder C and with it the cam 67 and the arm 69. In passing from the position shown in solid lines in Fig. 3, the cam moves away from the inner surface of the lip 14 of the 40 slide plate 13 (Figs. 2 and 3) and when the arm 69 is moved to its extreme position, it presses the lug 70 of the lock 71, and thereby withdraws said bolt from the door casting or catch as aforesaid. The slide plate 13 45 is consequently left in its closed position and still conceals the dials 38 from sight, but by inserting a pin or suitable instrument having a sharp point, into the hole 15 of the slide plate 13, (Fig. 1) the latter can 50 be manually moved to the right (to the position shown by dotted lines in Fig. 3) to uncover the counter register. The difference between the number shown on the dials 38 and the number shown at the last previous 55 reading of the dials indicates the number of coin actuated operations since the last reading, and hence the number of coins that have been inserted in the lock by the patrons thereof. After the dials have been 60 read, the cylinder 6 and its associated parts are turned back by the key 51 from the position in which the cam 67 is shown by dotted lines in Fig. 3 to the position in which the cam 67 is shown by solid lines. 65 In this way the bolt 71 is permitted to re-

turn to its former position by action of a spring (not shown), and the cam edge 68 of the cam 67 by its pressure against the lip 14 of the slide plate 13 automatically moves said slide plate from the position 70 shown by dotted lines to its position shown by full lines in Fig. 3 and so is locked in position.

Without limiting myself to the precise form and arrangement of parts, I claim:— 75

1. In a lock apparatus, the combination with its bolt and a lock case having an aperture, of a closure for the said aperture, a member which when moved in one direction acts upon the bolt and releases the closure, and which when moved in the opposite direction acts upon the closure and simultaneously releases the bolt. 80

2. The combination with a lock having a body with a keyhole and wards, a tubular sleeve in which said body is mounted, a cross pin fastening the body and sleeve together to turn in unison, and a key conformed to the body to enter and turn the same; and a counting device and means to 85 actuate the same; of a case within which said lock, counting device and counter actuating means are mounted, which case is provided with an aperture through which to read the counting device, a sliding plate 90 movable in said case across said aperture, and a cam connected with the sleeve of the lock and movable therewith to encounter and move said sliding plate, to cover said aperture and conceal and protect the counting device, when said sleeve and body are turned by the key. 100

3. In a lock apparatus, the combination with a case, a bolt movable in the case, means to operate the bolt, a counter to record the number of movements of the bolt through the means aforesaid, and operative connections between the counter and said operating means, of a device to screen the counter, and a second bolt operating device 105 110 which also acts upon the screening device.

4. In a lock apparatus, the combination with a case, a bolt movable in the case, two independent bolt operating devices, a counter to record the number of operations 115 of one bolt operating device, means to connect the counter and said device, and a closure to screen the counter controlled by the other bolt operating device.

5. In a lock apparatus the combination 120 with a case having an aperture, and a bolt movable in the case, of a counter within the case to record certain movements of the bolt, the register of said counter being at the aperture aforesaid, means through 125 which the bolt, in such certain movements, actuates the counter, a closure for the said aperture, and two independent bolt moving devices, one of which devices acts simultaneously upon the bolt and upon the counter 130

- but not upon the closure, and the other of which devices acts simultaneously upon the bolt and upon the closure but not upon the counter.
5. 6. In a lock apparatus, the combination with its bolt, main controlling device to operate the bolt, a lock case having an aperture, and a closure for the aperture, of a supplementary bolt actuating device comprising a cylinder, a bearing in which one end of the cylinder turns, a trunnion entering the opposite end of the cylinder on which the cylinder turns, the cylinder being made with two arms, one of which arms engages the bolt to move it with turning of the cylinder, the other of which arms normally engages the closure to lock it from movement and means to turn the cylinder to move the bolt and to release the closure.
- 10 7. In a lock apparatus, the combination with the bolt, a main operating device to work the bolt, a counter to record the workings of the bolt by the main operating device, and a case for the foregoing having a sight aperture for the counter register, of a closure for said aperture, a secondary device to work the bolt independently of the counter, means through which the secondary device in its normal position locks the closure in its closed position, and means to operate the secondary device to work the bolt and simultaneously release the closure.
- 15 8. In a lock apparatus having a bolt and a main bolt operating device, the combination with a lock case having a bearing 7 and aperture 6, the lever 18 of the main bolt operating device, a counter facing the aperture 6 and connections between the lever 18 and the counter, of a plate 20 secured with- 20 in the case, a trunnion 34 on said plate and in line with the bearing 7 of the case, a closure for the aperture 6, a member C mounted to turn in the bearing 7 and on the trunnion 34, to encounter, and obstruct the movement of, the closure, and means to turn the member C to effect such encounter and obstruction.
- 25 9. In a lock apparatus having a bolt and a main device for controlling the bolt, the combination with the lever 18 of said main device, and the case for the lock having a bearing 7 and a sight aperture 6, of a plate 20 within the case, a counter mounted thereon opposite the sight aperture 6, means mounted on the plate to connect the counter 55 with the lever 18, a trunnion 34 also mounted on the plate 20, axially in line with and opposite the bearing 7, a movable closure for the aperture 6, a member C which is mounted in the bearing 7 and on the trunnion 34 and which in normal position encounters and restrains the closure from movement, and which when turned withdraws said restraint from the closure but 60 encounters and works the bolt, and means 65 to turn the member C.
10. In a lock apparatus having a bolt and an operating device therefor, the combination with the lever 18 of said operating device and the case of the lock, which case is formed with a bearing 7 and with an aperture 6 and ways adjacent said aperture, of a sliding closure mounted in said ways, a plate 20 secured within said case, a counter mounted on the plate opposite said aperture, a lever 22 mounted on the plate 20 and operatively connecting the lever 18 with the counter, a trunnion 34 also mounted on the plate 20 in line with and opposite the bearing 7, a member C mounted to turn in the bearing 7 and on the trunnion 34 to encounter and control the closure and means to turn the member C.
- 15 11. In a lock apparatus having a principal lock operating device, the combination with a lever 18 of said device, the lock bolt, the case for the lock formed with a bearing 7 and a sight aperture 6, and a closure for the sight aperture, of a plate 20 secured within the case, a counter mounted on the plate opposite the aperture, a lever 32 mounted on said plate and operatively connecting the lever 18 with the counter, a locking disk 34, also mounted on the same plate axially in line with and opposite the bearing 7, a member C mounted to turn in the bearing 7 and on the locking disk 34 as on a trunnion, the said member C encountering the closure to lock the same shut, and a key to turn the member C for the purpose 100 specified.

In testimony whereof I affix my signature in presence of two witnesses.
